Jeff Montgomery

ATTORNEY

UNITED STATES PATENT OFFICE

149,125

DESIGN FOR A NOVELTY SOAP AND WASH CLOTH DISPLAY DEVICE

Juliana Gardiner Johns, Orange, N. J.

Application July 19, 1946, Serial No. 131,706

Term of patent 3½ years

(Cl. D80—5)

To all whom it may concern:

Be it known that I, Juliana Gardiner Johns, a citizen of the United States, and a resident of Orange, county of Essex, and State of New Jersey, have invented a new, original, and ornamental Design for Novelty Soap and Wash Cloth Display Device, of which the following is a specification, reference being had to the accompanying drawing, forming part thereof.

Fig. 1 is a perspective view of the novelty soap and wash cloth display device showing my new design.

Fig. 2 is a perspective view thereof, with the cover raised.

I claim:

The ornamental design for a novelty soap and wash cloth display device, as shown.

JULIANA GARDINER JOHNS.
